WATER-COOLED ARC LAMP CARBON
HOLDER

Jesse A. Grayson, Los Angeles, Calif.

Application September 24, 1951, Serial No. 248,018

6 Claims. (Cl. 173—328)

1

The invention relates to carbon arc projectors regularly used in the projection of motion pictures and has particular reference to heavy-duty projection machines which would be suitable for use in out-of-door theaters employing oversize screens wherein, because of the intensity of heat produced by the arc over long periods of time, a cooling system becomes advantageous.

Water cooling attachments for projection arc lamps have heretofore been devised which reveal broadly one scheme or another for bringing cooling water into contact with a portion of the frame or casing supporting the carbon electrode. While these previously employed cooling schemes have effected some improvement upon standard construction wherein such cooling devices have been omitted, the previously employed cooling schemes have been defective in certain particulars. To a large extent they have been complicated by a large number of individual parts which when subjected over extended periods of time to high temperature conditions eventually become unusable and necessitate frequent servicing, repair and replacement. The cooling structure has also added considerable bulk to the electrode supports necessitating considerable waste of electrodes encompassed by the structure which might otherwise be burned to advantage. Schemes for cooling heretofore employed have necessitated exposed wiring which itself has been a cause of trouble because of deterioration and because of providing a path for electricity through portions of the device sufficiently circuitous to be a recurring source of trouble.

It is therefore among the objects of the invention to provide a new and improved water cooled arc lamp carbon holder which is relatively simple in construction to the end that fewer parts are required, a lesser quantity of metal is needed and wherein assembly operations are considerably reduced.

Another object of the invention is to provide a new and improved water cooled arc lamp carbon holder wherein most of the operating parts are contained within a single solid metal piece which comprises an efficient conductor for both heat and electricity.

Still another object of the invention is to provide a new and improved water cooled electrode holder for projection arc lamps in which the cooling water is maintained in a continuous state of flow, thereby to more effectively remove the heat and also one wherein such a relatively small portion of the electrode is clamped in and encompassed by the holder that virtually all of the elec-

2

trode in every instance except a short clamped portion may be usefully consumed in producing the arc.

Still another object of the invention is to provide a new and improved water cooled electrode holder for projection arc lamps which is capable of effectively consuming all but a small portion of electrodes of varying sizes and styles whether jacketed or unjacketed.

Still further among the objects of the invention is to provide a new and improved water cooled electrode holder which is particularly easy to operate when exchanging electrodes burned virtually to the end for new full-length electrodes, thereby effecting a substantial saving in the operation of the projecting lamp.

With these and other objects in view, the invention consists in the construction, arrangement and combination of the various parts of the device whereby the objects contemplated are attained, as hereinafter set forth, pointed out in the appended claims and illustrated in the accompanying drawings.

In the drawings:

25 Figure 1 is a side elevational view of a conventional projection arc lamp partly broken away to reveal the arrangement of the interior.

Figure 2 is a top plan view of the water cooled arc lamp carbon holder and water connections therefor drawn to a larger scale.

30 Figure 3 is a front elevational view partially in section showing the frame and appurtenances of the carbon holder.

Figure 4 is a partial side elevational view in section taken on the line 4—4 of Figure 3.

Figure 5 is a rear elevational view partially in section of the portion of the holder shown in Figure 4.

40 Figure 6 are views of different styles of carbon electrodes adapted for use in the holder.

In the construction of water cooling attachments previously employed for the cooling of projection arc lamps resort was had to a series of contractable brushes of conducting material arranged so as to be resiliently drawn together in order to make electric contact with the electrodes. Practice finally dictated the employment of very heavy low resistance copper wires commonly called pigtails as a means of conducting electricity directly to the brushes to promote good performance. Without the auxiliary pigtails the device was prone to burn out. In the older types of water cooling attachments a chamber of water was maintained in a jacket around the electrode, the chamber being of such volume as to inhibit

rapid passage of cooling water, thereby setting a limit on the cooling effect produced by the flow of water. The construction also promoted use of an enlarged head or nose piece 44 setting the burning point of the electrode outwardly at some distance from the water jacket. Although this structure encompassed advantages due to the utilization of water cooling in devices of the character described, the limitations noted among others suggested the necessity of still further improvements.

In the embodiment herein selected to illustrate the invention there is shown in Figure 1 a lamp housing 10 of the style currently in use for projection arc lamps. In this arrangement a projector 11 is ordinarily located at one side so that an arc 12 produced by the charged electrodes reflects from a mirror 13 through the projector. A stationary frame 14 locates one movable electrode 15 while another electrode 16 is stationarily mounted by conventional means on the focal axis of the reflecting mirror.

Still further, following conventional construction, there is provided a feed carriage 17 to which one end of the electrode 15 is secured by a screw 18. The feed carriage is usually mounted so as to slide upon a track 19 and is connected to an advancing screw 20 manipulated by a timing mechanism (not shown) to the end that the electrode 15 may be progressively advanced by automatic means so that the burning end continues to be correctly spaced from the burning end of the electrode 16 as the electrode is consumed during operation. This of course has been well known in the art and in commercial use for some number of years.

The stationary frame 14 illustrated in greater detail in Figures 2 through 5, inclusive, is shown as an elongated member having a free upwardly disposed end 25 and a lower anchoring end 26. The anchoring end is shown as attached to a block 27 which is part of the lamp housing. So that the frame may be insulated electrically from the block 27, an insulating piece of sheet material may be interposed between the frame and the block and a bolt 28 is set in a sleeve 29 of insulating material so that the bolt does not come into contact with the frame. The sheet of insulating material may be secured by screws entering threaded holes 32 and 33 shown in phantom view in Figure 3, the screws being counter-sunk in the insulating material in conventional fashion to keep the screw heads out of contact with the block 27. Electric contact is made with the frame by an electric cable 34 attached to a binding post 35 at the rear face of the frame and out of contact with the block 27.

The frame is provided with a supply conduit 36 extending from a point 37 adjacent the anchoring end of the frame to the free end of the frame at a position outside the electrode 15. The supply conduit is fed by a metal tube line 38 connected by means of a metal fitting 39 to a manifold 40 attached to the lamp housing 10. The manifold 40 is insulated from the lamp housing by the interposition of an insulating sheet 41 so that there may be no direct passage of electricity through the metal portions of the device from the frame to the lamp housing.

Also within the frame and on the opposite side is a return conduit 42 which extends from the free end 25 to a point 43 adjacent the anchoring end. A second metal tube line 44 connects the return conduit to the manifold 40 previously described by means of a fitting 45. It will also be

noted that the supply conduit and return conduit are connected together by means of an outer intermediate conduit portion 46 and an inner intermediate conduit portion 47. In this fashion the supply and return conduits divide and form substantially an open rectangle for cooling water adapted to completely surround the electrode 15. The conduits mentioned may be formed in the frame following the conventional practice either by drilling the conduits and subsequently plugging access holes or by casting the conduits in place should the frame eventually be made by a casting method.

In the free end 15 of the frame there is provided an aperture indicated generally by the reference character 50 adapted to receive the electrode 15. It should be noted in this connection that the aperture comprises an inner cylindrical portion 51 larger in diameter than the outside diameter of the largest electrode which would ordinarily be used in the device. An intermediate cylindrical portion 52 adjoins the cylindrical portion 51 and an outwardly directed flared portion 53 adjoins the cylindrical portion 52 and opens upon the face of the frame 14 adjacent a burning end 54 of the electrode 15. By this construction it will be noted from the relative location of the electrode 15 that there is contact between the frame and the electrode only throughout the lower circumference of the cylindrical portion 51. The electrode will be slightly clear of the frame throughout the area occupied by the cylindrical portion 52 and entirely free of the frame within the flared portion 53. Constructed in this fashion as the electrode burns down close to the frame the cooling effect on the stubbed burning end of the electrode will not be so great as to impair its efficiency and brightness.

To hold the electrode 15 in position there is provided on the face of the frame opposite from the burning end of the electrode a clamp comprising one stationary clamp block 55 and one movable clamp block 56. The stationary clamp block is anchored to the frame by means of screws 57 and 58. Guide holes 59 and 60 extend through the stationary clamp block on opposite sides as illustrated in Figure 5. As best seen in that figure, pins 61 and 62 fit slidably in the guide holes and are threadably connected to the movable block 56 at ends 63 and 64 of the pins. A cross head 65 connects the lower ends of the pins and supports a compression spring 66 biased to continually draw the pins 61 and 62 downwardly, thereby tending to draw the block 56 down against the block 55. The block 55 is provided with a semi-cylindrical recess 67 having a radius at least as large as the radius of the largest electrode to be encountered. The block 56 has a similar complementary partially cylindrical recess 68. The recesses 67 and 68 are adapted to clamp between them the exterior circumference of the electrode 15. It will therefore be apparent that only throughout the length of the electrode measured by the thickness of the blocks 55 and 56 is the electrode contacted on both sides by metallic elements. The pressure exerted by the spring 66 tending to draw the block 56 against the electrode is not sufficiently great to prevent sliding the electrode 15 through the clamping arrangement as the carriage 17 is fed by the mechanism to advance the electrode 15 toward the electrode 16.

When the device is to be operated, the electrode 16 is set in position and the electrode 15 is then

inserted into the frame. The end of the electrode may be guided by means of a guide slot 69 so as to more readily find the hole formed between the complementary recesses 67 and 68. The movable block 56 may be lifted to enlarge the recess by pressing outwardly upon the cross head 65. The electrode 15 need be initially inserted to a relative position no more nearly approaching the electrode 16 than suggested by Figure 4. The electrode will, however, operate satisfactorily when held even closer to the frame 14. After the electrode has been positioned, the carriage 17 may be placed behind it and the feed mechanism started after the current is turned on and the arc 12 begins to operate. As the electrode 15 is consumed during burning, the electrode is gradually fed forward until the rightmost end of the electrode is positioned virtually flush with the exposed face of the block 55. During operation cooling water is circulated through the supply conduit 38, thence around the electrode through the intermediate conduits 46 and 47, and finally out through the return conduit 42. It will be noted that there is a constant flow of cooling liquid entirely surrounding the electrode at the hottest point. The burning tip of the electrode is, however, kept far enough away from contact with the metal so that the burning tip maintains the high temperature needed for a bright arc.

Electrodes of any diameter up to a diameter equal to the diameter of the cylindrical portion 51 may be utilized. Electrodes of considerably smaller diameter operate successfully as illustrated by the figures of the drawing and the description heretofore supplied. It will also be appreciated that electrodes may be pure carbon electrodes like the electrode 15' of Figure 6, copper jacketed electrodes like the electrode 15'' of relatively large diameter, or copper electrodes like the electrode 15''' of relatively smaller diameter.

When it is appreciated that the flared portion 53 is substituted for a protruding nose piece in order to insulate the hot burning arc from the frame, the electrode can be consumed to a much shorter length than heretofore. Also by omitting a water jacket surrounding the electrode and limiting the liquid cooling passages to a free flowing passage immediately adjacent the electrode, the space which would ordinarily be occupied by the jacket is dispensed with and again the electrode is permitted to be burned down that much shorter. In present day commercial practice it takes about a five-inch length of carbon electrode to run one reel of film. Carbons are ordinarily made in twenty-inch lengths. Where under present circumstances carbons can be burned down to about one inch remaining length rather than to about five inches of remaining length following practices heretofore employed, it will be appreciated that fewer changes of carbon are necessary for a night's run of film. Moreover, when the cost of electrodes at \$19 to \$20 each is considered for each twenty inches of length, there is made possible a 25% saving of electrode material for each electrode burned. When copper jacketed electrodes are used, the saving of metallic material and cost is considerably greater. It will further be appreciated that comparable savings may be enjoyed when carbons of as short as fourteen inches are used. Commercial carbons of this length have been found highly unsatisfactory in conventional projection lamps because of their shortness where at the usual rate of consumption the fourteen-inch carbons could be

counted on to last no longer than two reels of film.

By the provision therefore of a carbon holder wherein the sum total number of pieces and the number of moving parts have been reduced substantially to a minimum and have been fabricated to retain and encompass but a very short section of electrode and further wherein continuous cooling at the point of clamping makes it possible to clamp only the shortest possible section, a highly efficient, inexpensive and greatly improved device results.

While I have herein shown and described my invention in what I have conceived to be the most practical and preferred embodiment, it is recognized that departures may be made therefrom within the scope of my invention, which is not to be limited to the details disclosed herein but is to be accorded the full scope of the claims so as to embrace any and all equivalent devices.

Having described my invention, what I claim as new and desire to secure by Letters Patent is:

1. A water cooled electrode holder for projection arc lamps comprising a solid metal frame having an electrode-receiving aperture therein having a diameter at one end not less than the outside diameter of the largest electrode to be used, said aperture having a progressively expanding diameter from said one end toward the other end thereof, a continuous conduit in the frame of uniform cross-sectional area having a portion surrounding said aperture and having supply and return portions extending through the frame, and an electrode holder comprising one block forming part of said frame having an arcuate recess in axial alignment with said aperture, a second movable block having a complementary arcuate recess therein adapted to receive an electrode with the first block, and spring means associated with said block adapted to draw the movable block into electrode holding position.

2. A water cooled electrode holder for projection arc lamps comprising a stationary frame having an electrode-receiving aperture therein, one end of said aperture comprising a cylindrical portion larger in diameter than the electrode of largest diameter, and the other end comprising a flared portion expending progressively outwardly from the cylindrical portion, a supply conduit for cooling water extending through the frame on one side of the aperture, a return conduit extending through the frame on the other side of said aperture, intermediate conduit means on still other sides of said aperture connecting the supply and return conduits whereby the aperture is encompassed by said conduits, metal water lines connected to said inlet and outlet conduits, an electric connection to the frame at a location remote from said aperture, and an electrode holder on the frame adjacent said aperture comprising an arcuately recessed block divided into a stationary portion mounted on the frame, a movable portion, and spring-biased guide means in the stationary and movable portions adapted to draw said portions toward each other to the electrode holding position.

3. A water cooled electrode holder for projection arc lamps comprising an elongated stationary frame having at a free end an electrode-receiving aperture and at an anchoring end an insulating mounting device, said aperture comprising a cylindrical end portion larger in diameter than the electrode of largest diameter, an intermediate cylindrical portion of larger diameter than said end portion and an outwardly directed

flared portion at the other end, a supply conduit for cooling water extending through the length of the frame from said anchoring end to the free end on one side of the aperture, a return conduit extending through the frame from said free end at the other side of the aperture to said anchoring end, intermediate conduit portions on still other sides of said aperture connecting the supply and return conduits whereby the aperture is encompassed by said conduits, a conduit supply manifold and metal water lines connecting said manifold with said inlet and outlet conduits, an electric connection at the anchoring end, and an electrode holder on the frame adjacent said cylindrical portion of the aperture comprising an arcuately recessed block divided into a stationary portion mounted on the frame, a movable portion, and spring-biased guide means in the stationary and movable portions adapted to draw said portions toward each other to electrode holding position.

4. A water cooled electrode holder for projection arc lamps comprising a stationary frame having an electrode-receiving aperture and an insulating mounting device, said frame having an electrode-receiving aperture having a progressively increasing diameter from a cool side of the frame to a hot side thereof, means forming a continuous water circulating conduit in the frame around said aperture, an electric connection to the frame and an electrode clamp on the cool side of the frame comprising complementary recessed blocks with the center of the recess in axial alignment with the aperture and adapted to receive an electrode therebetween, one of said blocks being anchored to the frame, the other of said blocks having guide means at the side of the complementary recesses extending through the first blocks, spring means acting between one of said blocks and the guide means adapted to move said one block against the other block.

5. A water cooled electrode holder for projection arc lamps comprising an elongated stationary frame having at a free end thereof an electrode-receiving aperture and at another end an

insulating mounting device, said frame at the free end thereof having an electrode-receiving aperture having a progressively increasing diameter from a cool side of the frame to a hot side thereof, means forming a continuous water circulating conduit in the frame from the anchoring end to said aperture and around said aperture and back to the anchoring end, an electric connection to the frame at the anchoring end and an electrode clamp comprising complementary recessed blocks adapted to receive an electrode therebetween, one of said blocks being anchored to the frame adjacent the aperture, the other of said blocks having guide pins on opposite sides thereof extending through the first block, spring means acting between said first block and the pins adapted to move said second block against the first block.

6. A water cooled electrode holder for projection arc lamps comprising an elongated stationary frame having at a free end thereof an electrode-receiving aperture and at another end an insulating mounting device, said frame at the free end thereof having an electrode-receiving aperture having a progressively increasing diameter from a cool side of the frame to a hot side thereof, means forming a continuous water circulating conduit in the frame from the anchoring end to said aperture and around said aperture and back to the anchoring end, an electric connection to the frame at the anchoring end and an electrode clamp comprising complementary recessed blocks adapted to receive an electrode therebetween, one of said blocks being anchored to the frame adjacent the aperture, the other of said blocks having guide pins on opposite sides thereof extending through the first block, spring means acting between said first block and the pins adapted to move said second block against the first block, and a slot on the exposed side of one of said blocks terminating at the recess therein adapted to direct an electrode end into the recess.
